SHUTTLE FOR THREAD CUTTERS

Application filed February 21, 1931. Serial No. 517,560.

This invention relates to improvements in shuttles adapted for cooperation with thread parters and it is the general object of the invention to provide a shuttle carrying means so placed with respect to the weft delivered by the shuttle as to assist in the action of a thread parter external to the shuttle.

In weft replenishing looms the outgoing bobbin at the time of transfer leaves a piece 10 of thread which extends from the adjacent selvage through the shuttle eye and to the bobbin. Unless this thread is extracted from the shuttle box it is likely to be whipped into the shed when the freshly replenished shuttle is picked. It is an important object of any present invention to employ a plate or the like on the front wall of the shuttle positioned adjacent the delivery eye of the latter and located between said delivery eye and the adjacent selvage so as to cooperate with a thread parter which may be brought into action to 20 part the thread at the time of weft replenishment.

Shuttles of the type to which this invention 25 relates are generally provided with a longitudinal thread groove in substantial alignment with the delivery eye of the shuttle, the groove providing a chamber in which the thread may lie without requiring the same 30 to be pinched between the binder and the front wall of the shuttle. It is a further object of my present invention to provide the thread plate in the front wall of the shuttle and located so as not to protrude objectionably into the thread groove. When so placed 35 the plate will be out of engaging position with respect to the binder and there will be no tendency to pinch the thread between the shuttle and the binder as the shuttle is boxed.

40 It is a more specific object of one form of my invention to employ the usual bolt which holds the shuttle block in position to also retain the thread plate in its position in the front wall of the shuttle.

45 With these and other objects in view which will appear as the description proceeds, my invention resides in the combination and arrangement of parts hereinafter described and set forth in the claim.

50 In the accompanying drawing, wherein I

have shown my invention applied to two different forms of shuttle,

Fig. 1 is a front elevation of a shuttle of the preferred form made according to my present invention,

55 Fig. 2 is a top plan view of a shuttle shown in Fig. 1,

Fig. 3 is a view similar to Fig. 1 but showing the modified form, and

Fig. 4 is a vertical section on line 4—4 of Fig. 3 showing the manner of holding the 60 thread cutter plate in position.

Referring to Figs. 1 and 2 I have shown the preferred form of shuttle as having a weft chamber 10 having provision as at 11 65 to support a bobbin so that the same may be expelled at the time of weft replenishment. The opposite end of the shuttle is provided with a thread passage 12 in which is located a tension designated generally at 13. Leading 70 forwardly from the chamber 12 is a delivery eye 14 the forward end of which is in substantial horizontal alignment with a shallow thread groove 15 extending throughout a greater part of the length of the shuttle 75 as set forth in Fig. 1.

The shuttle set forth in this form of the invention may be substantially the same as that shown in patent to Hutchins No. 1,723,423. Such shuttles employ a cover 16 which 80 may be held in position by a vertical bolt 17. The tension device 13 comprises movable elements which place the weft on the tension during the weaving operation. That part of the shuttle which has already been described 85 of itself forms no part of my present invention but is a type which has been successfully used in the weaving of finer yarns.

In carrying my invention into effect in its preferred form I cut a recess 20 in the front 90 wall 21 of the shuttle and insert therein a plate 22, the front wall 23 of which preferably does not extend into the passage defined by the groove 15. While I prefer this construction yet the invention will operate if the surface 23 extends forwardly with respect to the rearmost part of the groove 15. The plate may be held in position by means of screws 24 screwed into the front wall of the 95 shuttle. By reference to Fig. 1 it will be seen 100

that the plate extends above and below the groove 15 and the delivery eye 14 so that the weft designated at W leading from the eye 14 to the left back to the adjacent selvage when the shuttle is in replenishing position will extend across the plate 22. A cutter 25 having a cutting head 26 is positioned to engage the plate 22 when the shuttle moves forwardly on a transferring beat of the loom. The cutting edge 27 of the head engages the weft and pinches the same against the plate 22 so as to cut the filling at a point very close to the eye of the shuttle. The outgoing bobbin is therefore able to carry with it the comparatively short length of thread extending from the plate to the right through the eye 14 and back into the thread chamber 10. For this reason a comparatively slight thread withdrawing action on the part of the outgoing bobbin will suffice to clear the shuttle eye.

In the modified form of the invention set forth in Figs. 3 and 4 the shuttle is provided with a front wall 30 having therein a recess 31 similar to recess 20, the plate 32 being non-circular and fitting into the recess 31 so as to be held against displacement vertically or in a direction parallel to the axis of the shuttle. The plate has a boss 33 which receives the forward threaded end of a screw 34. The latter extends through the usual shuttle block 35 and has a head 36 accessible from the rear wall of the shuttle. As in the preferred form of the invention, the shuttle has a delivery eye 37 which lies intermediate the vertical extremes of the plate 32 and therefore is positioned to engage the weft when the latter is pinched thereagainst by the cutter. In the preferred form the cover holding screw extends vertically whereas in the modified form the screw extends horizontally and can therefore be made use of in holding the thread plate in position. In the modified form the screw does not extend forwardly to the front face of the plate so that the latter is continuous within its outside perimeter to coact properly with the cutter.

From the foregoing it will be seen that I have provided a very simple form of plate or the like on a shuttle to coact with a thread parter, the plate being located very close to the delivery eye of the shuttle and extending so as to insure proper location with respect to the thread to be cut. It is to be understood that the weft cutter has a sufficient vertical dimension to engage the weft. It will also be seen in the modified form that the bolt 34 serves not only to hold the shuttle eye in position but also places the plate 32 so that it cannot become dislodged by forward movement with respect to the shuttle. In the modified form the shuttle block may be of the more usual form wherein the weft engaging surfaces are stationary with respect to the shuttle, tension being caused by the character of surface which contacts with the weft.

It is to be understood that my invention is not dependent upon the particular kind of shuttle eye used although the position of the delivery eye in either form has a definite relation with respect to the location of the plate.

The plates which coact with the thread parter head 26 are preferably made of hardened steel, although I do not wish to be limited to this material as the purposes of this invention will be accomplished if the plate is harder than the yarn and coacts with the weft cutting head to part the filling either by a cutting or a breaking action.

Having thus described my invention it will be seen that changes and modifications may be made therein by those skilled in the art without departing from the spirit and scope of the invention and I do not wish to be limited to the details herein disclosed, but what I claim is:

In a weft parting shuttle having a shuttle eye block and a delivery eye in fixed relation with the block and aligning with a longitudinal thread groove, means presenting a relatively hard surface set in an exterior portion of the shuttle and having said surface extending across the groove, and securing means carried by the shuttle and holding the first named means and the block securely to the shuttle, the first named means being positioned to coact with a thread parter to sever a thread extending across said surface.

In testimony whereof I have hereunto affixed my signature.

OSCAR V. PAYNE.
